UNITED STATES PATENT OFFICE.

CHARLES F. MAGUIRE, OF HAVERHILL, MASSACHUSETTS.

DESIGN FOR A BOOT OR SHOE.

SPECIFICATION forming part of Design No. 34,733, dated July 2, 1901.

Application filed May 20, 1901. Serial No. 61,199. Term of patent 7 years.

To all whom it may concern:

Be it known that I, CHARLES F. MAGUIRE, a citizen of the United States, and a resident of Haverhill, county of Essex, Massachusetts, 5 have invented and produced a Design for a Boot or Shoe, of which the following is a specification.

This invention consists in the particular pattern or design of the instep portion of a 10 boot or shoe of that class in which a piece of goring contrasting in shade and appearance with the upper-leather of the shoe is inserted at the instep of the shoe; and it comprises a relative arrangement, configuration, and outline of the upper-leather surrounding and adjacent to said goring.

In the drawing I have shown a lady's laced boot which embodies the essential features of my design.

20 In the drawing, *a* designates the vamp or upper of the boot, and *b* the top, into which is inserted the goring *c* at the instep portion thereof. The seam *a'*, which unites the lower part of the top to the vamp *a*, extends for a short 25 distance horizontally and lengthwise of the shoe and then curves inward to a central point, as indicated at *a''*, this seam being made prominent, so as to form a prominent feature of the design. The sides of the goring are 30 defined by the substantially straight edges

b', which extend from the seam *a'* to the flaps or fly portions *b''* of the top of the shoe.

d designates an ornamental pattern or piece of leather which may have the same appearance as the rest of the upper-leather, so as to 35 contrast with the goring *c* and which is formed with a long slender tongue *d'*, extending nearly to the top of the goring through the center thereof, and whose edges have a curved or scroll-like outline. The lower or base 40 portion of said insertion *d* extends laterally and rearwardly with a symmetrically-curved outline to a point near to the junction of the edge *b'* with the edge or seam *a'*.

The essential feature of the design 45 comprises a gored instep-piece *c* with the sloping and substantially straight side edges *b'*, extended down to meet the seam *a'* and being partly covered with the ornamental insertion *d*, having the scroll or convoluted edges, 50 substantially as described.

What I claim is—

The design for a boot substantially as herein shown and described.

In witness whereof I have hereunto set my 55 hand this 15th day of May, 1901.

CHARLES F. MAGUIRE.

In presence of—

JOHN E. MAGUIRE,
E. RUSSELL FIELD.
